CHILD'S SLEEPING GARMENT

Filed June 7, 1948

UNITED STATES PATENT OFFICE

2,621,336

CHILD'S SLEEPING GARMENT

Louis Wendorff, New York, N. Y.

Application June 7, 1948, Serial No. 31,485

1 Claim. (Cl. 2-227)

1

This invention relates to a sleeping garment for children.

It is a well-known fact that young children frequently kick off their bed covers and blankets at night. On relatively cold nights this fact endangers the health of the child since it unduly exposes the child to conditions which are productive of colds and similar ailments. It is also a well-known fact that children of tender years wet their clothes at night and this fact, coupled with the first-mentioned fact, can lead to serious consequences with respect to the child's health.

The principal object of this invention is the provision of a sleeping garment for children, which provides the warmth and protection of a blanket and at the same time prevents soiling of the bedclothes which is generally caused by wetting. The garment herein claimed may be made of blanket material or other suitable material, and it is so designed that it covers or clothes the child's entire body including its limbs and up to its neck, over its pajamas. It cannot be thrown off by the child since it is provided with fastening means which secure it about the child's body. The child is therefore fully covered at all times but it remains completely unrestricted and unconfined as to its normal bodily movements. No matter how the child twists or turns he remains covered at all times by the garment herein claimed.

The garment includes as one of its principal features a water-proof lining which prevents soiling of the bedclothes and indeed also prevents soiling of the garment itself, by reason of the child's wetting. This lining is removable so that it may be separately washed, without having to wash the entire garment at the same time.

A preferred form of this invention is shown in the accompanying drawing, in which:

Fig. 1 is a front view, partly broken away to expose the inner lining.

Fig. 2 is a front view of the inner lining, showing it wholly removed from the outer garment.

Fig. 3 is a section through the end of one of the sleeves on the line 3-3 of Fig. 1.

Fig. 4 is a section through the foot of one of the legs of the outer garment, said section being taken on the line 4-4 of Fig. 1.

Fig. 5 is a section through the inner lining on the line 5-5 of Fig. 2.

Fig. 6 is a fragmentary, perspective view of one of the legs of the inner lining and more especially of the lower end thereof.

As has above been indicated, the garment herein claimed comprises an outer garment 10 hav-

2

ing an inner lining 11. The outer garment is made of blanket material or such other material as may provide the necessary warmth and protection as of a blanket. The inner lining is made of water-proof material, preferably a water-proof plastic material. As is shown in the drawing, the inner lining, as has above been indicated, is removably insertable into the outer garment so that it may be inserted or removed at will.

10 The outer garment is constructed as an integral cover for the entire body up to and including the neck. It includes, therefore, a body portion 20, a pair of sleeves 21 and 22 respectively, and a pair of leg portions 23 and 24, respectively.

15 It has a front opening with a slide fastener closure 25. The front of this garment may be described as being of the double-breasted type where one front flap 26 overlaps the other front flap 27. The slide fastener provides a closure between the front edge of flap 27 and button-holes 29 along the front edge of flap 26 provide an additional closure for the front of the garment, this closure being along the front edge of said overlapping flap 26.

20 25 The front opening extends from the neck opening 30 to the crotch 31. This makes for great ease in dressing the child with the garment herein claimed. The opening is sufficiently large to allow the child's body to pass therethrough without great difficulty. The double closure provides double assurance that the garment will remain closed at all times and under all conditions until the person taking care of the child wishes to open it.

30 35 Each sleeve has a hand portion 40. This hand portion accommodates the entire hand and it actually encloses the hand. It will be noted in Fig. 3 that a seam 41 provides a closure for the end of the hand portion 40. A slit-shaped opening 42 is provided at the palm, or even above that, at the wrist, to provide access to the inside of the sleeve. This slit opening is placed so high that the child is normally unable itself to find it and thrust its hand therethrough. When it is desired to have the child's hands exposed, for the purpose of holding a milk bottle, or to play with toys, or for any other purpose, the hand portion of the sleeve may be rolled or folded back, leaving the slit-shaped opening as the farthest extremity on the sleeve.

45 50 It will be apparent from an examination of Fig. 4 that each leg portion of the outer garment has a foot portion 50 and a heel portion 51. This construction makes for considerable comfort to the child.

It is noteworthy that seams have been reduced to a minimum in the outer garment construction above described. It is recognized that seams make for discomfort and for this reason they have been eliminated from the construction under discussion wherever possible.

The inner lining 11 comprises three main portions: A body portion 60 and two leg portions 61 and 62 respectively. Each portion is made of a single unitary sheet of water-proof material. Leg portion 61 has a single seam 63 which extends its full length along its outer side and around its foot portion, and leg portion 62 has a similar seam 64 which extends its full length along its outer side and around its foot portion. Seams 65 and 66 respectively join the leg portions to the body portion. Seams 67 and 68 close the two sides of the body portion 60 and a peripheral seam 69 encircles its upper periphery. It will be noted therefore that there is no seam at the crotch 70 and no seam along the inner portions of the two leg portions 61 and 62 respectively. Since the material of which the inner lining is preferably made is a plastic material these seams may be heat-sealed or a plastic cement may be applied to the edges in question. These edges need not be sewed since sewn seams are generally not as water-tight as are heat or cement-formed seams.

The body portion 60 of the inner lining extends from the crotch to a line well above the waist. It may actually be made to extend to the armpit region. It may be provided along its peripheral edge with an elastic strip 71 to provide a snug fit between it and the body of the child. The lower ends of the leg portions are provided with heels 72 corresponding to heels 51 of the outer garment.

It will be noted that there is no especial need for fastening members to fasten the inner lining to the outer garment. The mere fact that the legs of the inner lining project into the legs of the outer garment is sufficient to hold the inner lining in place in the outer garment. Moreover, the fact that the inner lining fits snugly about the body of the child, as does the outer garment, is sufficient assurance that there will be no displacement of the inner lining relative to the outer garment at the time both are being worn. The reference to snugness last above made is not intended to imply that either garment must fit tightly about the body of the child. It is intended merely to indicate that both the outer garment and the inner lining are form-fitting members as distinguished from the baggy affairs commonly known as sleeping bags.

In use, the child may be prepared in his regular pajamas and then the inner lining 11 is placed over the pajamas and then the outer part 10 of the garment is placed over the lining 11 and the pajama top in a well known manner.

The foregoing is descriptive solely of a preferred embodiment of this invention and it will, therefore, be understood that modifications and changes may be incorporated therein both as to

the material used, and the construction features thereof, without violating or departing from the basic principles of the invention. For example, if it be desired to use a button and button-hole construction or any other fastening arrangement to detachably attach the inner lining to the outer garment, this may very easily and very well be done within the broad scope of the invention. Should it be desired to substitute snap fasteners for the button and button-hole construction shown in the drawing, this too may readily be done within the scope of the invention. Other modifications will occur to those skilled in the art to take care of individual requirements and preferences.

Having thus described my invention, what I claim as new and desire to secure by Letters Patent, is:

An inner lining for a sleeping garment of the character described, said inner lining comprising a body portion which extends at least from the waist downwardly to the crotch, and a pair of leg portions connected thereto, said inner lining being entirely closed except at the top and being provided with an elastic band at the top to hold it snugly about the body of the wearer, said body portion and said leg portions being each composed of a single unitary sheet of water-proof plastic material folded upon itself, the edges of each leg portion sheet opposite its fold being secured together in a seam extending along the full length of the outer side of the leg and around its foot portion to the lower end of its fold line, the folded body portion comprising a front and rear panel with the fold constituting the crotch line between the two leg portions, and joining said leg portions at the upper end of the fold line of each leg portion, the corresponding side edges of said panels being joined together.
